SPINDLE FOR TUBULAR YARN CARRIERS

Deane A. Cabot, Rumford, R. I., and Fausto G. De Santis, Quincy, Mass., assignors, by mesne assignments, to Reconstruction Finance Corporation, Washington, D. C., a corporation of the United States

Application April 26, 1949, Serial No. 89,748

3 Claims. (Cl. 57—130)

1

This invention relates to spindles for spinning frames or analogous machines and more particularly, to a novel spindle structure especially adapted for use with top suspension tubular yarn carriers made of paper or of a cellulose fiber composition, which are well known yarn carrying devices the upper portion of which is designed to be securely fitted onto and in driving contact with a tapering tip element located at the top of the spindle blade.

The aim of the invention is to provide an improved spindle structure of this character having various features of novelty and advantage and which is particularly characterized by its simplicity in construction; by its economy in manufacture and permissible utilization of greater tolerances for fits between the parts; by the facility with which it may be assembled without distortion or eccentricity; and by its effectiveness in operation in that it provides for easy stripping after doffing, is capable of low power consumption and retains proper balance when rotating at high speed thereby avoiding the undesirable difficulties and problems of unbalance which must be dealt with to obtain true running spindles and which will occur when spindles of the tube type are used having barrels made of wood which material is subject to inherent differences in density in different portions of the barrel and to dimensional changes in shape or form thereof caused by heat and humidity variations.

With the above and other considerations in mind, it is proposed in accordance with the present invention to include in the rotating structure of the spindle between the whirl and a top tip element an intermediate barrel member in the form of a metallic tubular element in radially spaced encircling relation about the spindle blade and forming a permanent part of the spindle. According to one feature of the invention, the tube, in its preferred form, is composed wholly of a light weight metal, such as an aluminum alloy or a magnesium alloy, arranged to be secured at its opposite ends by frictional connection with an axial extension of the whirl and a tip element fast to the upper end of the spindle blade. The whirl with its axial extension and the tip element which forms the bobbin plug each are composed of a harder metal, such as cast iron and steel respectively. The tip element and the whirl extension each are provided with one or more resilient or elastic rings made of either solid natural or synthetic rubber compounds, of round cross-sectional form, one commercially available type being known under the trade name of "O" rings of which

2

one manufacturer is Linear, Inc., Philadelphia, Pennsylvania.

The various objects and advantages of this invention will be more apparent upon considering the following detailed description of a preferred embodiment of the invention illustrated in the accompanying drawings, and the novel features of the invention will be particularly pointed out in the appended claims.

10 In the drawings:

Fig. 1 is a vertical sectional view of a spindle constructed in accordance with this invention and rotatably supported in a customary mounting, and showing a tubular yarn carrier in normal operating position;

Fig. 2 is a fragmentary view in vertical section, on enlarged scale, showing the lower "O" ring in section and in a compressed state connecting the lower end of the tubular barrel member to the whirl;

Fig. 3 is a fragmentary view in vertical section, on enlarged scale, showing the top "O" ring in a compressed state connecting the upper end of the tubular barrel member to the tip member;

Fig. 4 is a perspective view of one of the elastic "O" rings prior to assembly on the spindle blade;

Fig. 5 is a fragmentary view in vertical section similar to that of Fig. 2 but on smaller scale and with the outer tubular spindle barrel and the paper yarn carrier removed;

Fig. 6 is a perspective view of the metallic retainer collar for the lower "O" ring, and shown prior to assembly on the tapered portion of the spindle blade within the whirl cup, and

Fig. 7 is a fragmentary sectional view of the lower cylindrical portion of the bobbin plug showing the normal circular cross-sectional form of the "O"-ring prior to its assembly and insertion within the tubular barrel member.

Referring first to Fig. 1, the spindle construction there shown comprises a blade member 10 which may be of the usual form and may be mounted for rotation in any usual or convenient manner relative to a stationary support or base

12 affixed to the usual spindle rail 13. The blade member 10 has a tapered upper portion 14, a cylindrical bearing portion 15 and a tapered lower portion 16 terminating in a conical end portion 17. A whirl 18 is fast to the lower part of the tapered portion 14 and includes an axial extension or acorn 20 the top of which is recessed (see Fig. 5) to present a cup-like portion 21 with an upstanding annular rounded peripheral flange 22 having a vertical inner wall 23.

In addition, the upper portion 14 of the blade

is equipped with an encircling tubular barrel member 25 consisting of a hollow metal cylinder or tube made of a light metal such as an aluminum alloy or a magnesium alloy....

Disposed interiorly of the cup 21 and pressed onto the tapered portion 14 of the spindle blade is a beveled retainer collar 26 of suitable metal having a smaller outer diameter than the inside diameter of the cup 21 to provide an annular groove 27 of square cross-section between the vertical inner wall surface of the cup 21 and the outer vertical circumferential face 28 of the collar 26.

Placed in the annular groove 27 between the retainer collar 26 and the inner vertical wall 23 of the flange 22 is a resilient or elastic "O" ring 30 of solid rubber-like material, made of either natural or synthetic rubber compounds, of round cross-sectional form.

In practice, the "O" ring 30 may be of such size and cross-sectional diameter that it will lie snugly against the bottom and side walls of the groove 27. In assembly of the tubular barrel 25 with the whirl and with the "O" ring 30 initially positioned within the groove 27, as just described, the lower end portion of the tube 25 is inserted into the cup 21 and has an easy sliding fit or a hand push fit with the inside wall surface 23 of the annular flange 22 until the lower end of the tube engages the adjacent upper corner portion of the ring 30 whereupon the tube 25 in being forced further downward against the "O" ring 30 thereafter causes the ring to be compressed and flattened against the bottom and vertical side walls of the groove 27, as shown in Fig. 2.

At its upper end the tube 25 abuts an annular shoulder 35, Fig. 3, disposed exteriorly around the lower part of a tapered tip element or bobbin plug 36 which is pressed onto the upper end of the tapered portion 14 of the spindle blade member 10. The bobbin plug 36 is there shown as having a stepped formation with a rounded top portion 37 and a tapered longitudinally extending body portion 38 which extends downwardly therefrom terminating at its base edge at the shoulder or step 35 formed at the meeting line of the reduced cylindrical end portion 39 with the body portion 38. The bobbin plug 36 is counterbored from its lower end to form the enlarged central cylindrical recess 40 extending inwardly of cylindrical portion 39 and communicating at its inner end with the central bore 41 in the top wall of the plug 36. The bore 41 has its sides formed to the same taper as the upper end of the tapered portion 14 of the spindle blade, and the tip is pressed tightly onto the spindle blade.

As shown in Fig. 3, the cylindrical lower end portion 39 of the bobbin plug 36 extends within the tube 25 and is slightly reduced and of smaller outer diameter than the inside diameter of the tube 25. The cylindrical portion 39 carries a resilient or elastic "O" ring 45 which is positioned within a peripheral groove 46 formed at an intermediate section of the cylindrical portion 39 and of square cross-section having flat parallel side walls normal to the axis of the cylinder 39, as illustrated in Fig. 3. The "O" ring 45 is of circular cross-section prior to its assembly and insertion within the tubular barrel 25, as illustrated in Fig. 7. The inner periphery of the "O" ring 45 is slightly less in circumference than the circumference of the bottom of the groove 46 in the bobbin plug 36 while the exterior peripheral circumference of the ring 45 is greater than the circumference of the inner cylindrical wall of

the tube 25 so that when the "O" ring 45 is forced into the upper end of the tube 25 the ring 45 will be compressed into the cross-sectional shape shown in Fig. 3 of somewhat elliptical cross-section with flattened peripheral portions abutting the side and bottom walls of the groove 46. Thus, when the "O" ring 45 is compressed within its associated groove, the ring flattens out from the circular cross-sectional form shown in Fig. 7 to that shown in Fig. 3 so that the peripheral portion of the ring contacting with the bottom of the groove 46 is flat as well as its outer periphery which directly contacts the inner cylindrical wall surface of the tubular barrel 25 at its top end. Likewise, both sides of the "O" ring 45 which are in contact with the side walls of the groove 46 become flattened out against the side walls since the width of the groove 46 is initially made slightly greater than the diameter of the circular cross-section of the "O" ring 45. In one practical embodiment of the invention the bobbin plug 36 carried in the groove 46 an "O" ring 45 the inside diameter of which was nine sixteenths of an inch and a circular section diameter of three thirty-seconds of an inch. The groove 46 was made one hundred eight thousandths of an inch in width or approximately fifteen thousandths of an inch wider than the circular section diameter of the ring 45 while the depth of the groove 46 was made such that the ring 45 of normal circular section, when installed in the groove 46, projected outwardly from the groove to the extent of from ten to twenty thousandths of an inch.

The bobbin or tubular yarn carrier shown in Figs. 1, 2 and 3 is of a conventional form and comprises a tapered tubular body portion 50 made of paper, laminated bonded cellulose fiber, or other suitable material having the desired length and wall thickness, and provided with an internal full-length taper conforming to that of the tapered portion 38 of the bobbin plug 36 so that when the bobbin is pushed firmly onto the bobbin plug the upper end portion interiorly of the bobbin will tightly engage the tapered exterior portion 38 of the bobbin plug and in this way establish a detachable but positive driving connection of the bobbin 50 with the bobbin plug 36.

According to the preferred method of assembling the parts of the spindle, the whirl 18 is first pressed onto the tapered upper portion 14 of the blade in accordance with the usual practice employed in the manufacture of spindles. Next the beveled retainer ring 26 is placed upon the tapered upper portion 14 of the blade and forced down into tight seating engagement with the bottom of the cup 21. The resilient "O" ring 30 is applied over the upper end of the blade member 10 and placed in the annular groove 27 between the retainer ring 26 and the inner wall surface of the cup 21.

Next, the barrel tube 25 is slid over the tapered upper portion 14 of the blade and pushed down into the cup until the lower end of the tube seats upon the "O" ring 30. The tapered tip or bobbin plug 36 then is placed upon the tip end of the tapered blade portion 14 and forced down thereon in a suitable manner, as by means of a hydraulic press, until the blade portion 14 is of a predetermined length as measured from the bottom of the whirl 18 to the top of the bobbin plug 36, after which the top end of the blade is cut off or ground off flush with the rounded top end 37 of the bobbin plug 36. When this occurs, the tapered top end of the blade portion will be tightly wedged into the bore 41 of the bobbin plug 36, the upper

end of the tube 25 will firmly abut the shoulder 35, the resilient "O" ring 30 will be deformed as shown in Fig. 2 under endwise pressure of the tube 30, and the resilient "O" ring 45 will be compressed laterally into generally elliptical or flattened cross-section, as shown in Fig. 3, to firmly grip the inner peripheral surface of the tube 25 at its upper end.

It is to be understood that the length of the spindle blade portion 14 will be made to suit the particular length of bobbin or tubular yarn carrier to be normally employed with the spindle and, since such bobbins or tubes are made in a variety of sizes and lengths, the spindle blade section 14 accordingly will be made slightly longer than the length required for the bobbin length selected and the excess material of the blade subsequently cut off after the bobbin plug 36 has been pressed tightly onto the blade at the desired predetermined location thereon with respect to the bottom of the whirl for the bobbin to be utilized.

It will be observed from the foregoing description that the present invention provides a novel form of spindle construction for tubular yarn carriers which in the course of assembly operations eliminates any possible chance of bending the blade member during pressing of the bobbin plug and tubular aluminum alloy or magnesium alloy barrel onto the spindle blade and whirl, respectively. It will be observed further that the "O" rings 30 and 45 effectively isolate substantially both end portions of the tubular barrel 25 from the cast iron acorn 20 of the whirl and the steel bobbin plug 36 respectively, thus eliminating any possibility of galvanic corrosion of the aluminum or magnesium tube 25 which will generally be subject to such attack in assemblies with steel, brass, copper, lead, tin or nickel when moisture or other conducting liquids penetrate into the joint.

What is claimed is:

1. A spinning spindle for tubular yarn carriers comprising a central support, a tip member fast to the upper end of said support, a whirl fast to said support and well spaced axially thereon from said tip, said whirl having an axial extension presenting an enlarged recess in its top end, a tubular barrel member spaced about said support and extending axially thereof between said whirl extension and said tip, said tip having a shoulder closing the upper end of said tubular member and a cylindrical lower end portion formed with a circumferential groove extending within the upper end portion of the tubular member and in radially spaced relation thereto, an annular resilient rubber member within said groove and in a compressed state radially between the inner surface of the upper end of said tubular member and the exterior of said cylindrical end portion of said tip, and an annular resilient rubber member within the recess of said axial extension of said whirl and in a compressed state

forming a bottom seat yieldably supporting the lower end of said tubular barrel member.

2. A spinning spindle for tubular yarn carriers comprising a blade member, a whirl fast to said blade member, the top of said whirl being recessed to provide a cup portion with an upstanding annular outer flange, a tip member fast to the upper end of said blade member, a tubular barrel member about and spaced from said blade member, said tube extending between said tip member and said whirl and having its lower end disposed within said cup and engaging the inner surface of said annular flange with a sliding fit, an annular resilient rubber "O" ring member within said cup and abutting the bottom end of said tube, said ring being held in a compressed state to seat and yieldably support said tube, and an annular resilient rubber "O" ring member in a compressed state and radially disposed between the upper end portion of said tube and said tip member.

3. A spinning spindle for tubular yarn carriers comprising a blade member, a whirl fast on said blade member and having an axial extension the top of which is formed with a cup-like recess, a tip member fast to the upper end of said blade member, a tubular barrel member spaced about and extending between said whirl and said tip, said tip abutting the upper end of said tube and having a reduced cylindrical lower end inserted within but spaced radially from the upper end portion of said tube, an annular resilient rubber "O" ring member carried by said reduced end portion of said tip and having a tight fit within the upper end of said tube, the lower end of said tube extending within said cup-like recess of the whirl and engaging the annular outer walls of said cup with a push-fit, an annular metallic retainer member within said cup and fast to said blade member, the outer peripheral surface of said retainer member and the inner wall surface of said cup defining an annular groove within said cup, and an annular resilient rubber "O" ring member within said groove and being held in a downwardly compressed state to form a bottom seat yieldably supporting the lower end of said tube within said cup.
